UNITED STATES PATENT OFFICE.

CHARLES WOKES, OF TORONTO, ONTARIO, CANADA.

CHEMICAL FIRE-EXTINGUISHING APPARATUS.

1,141,293.

Specification of Letters Patent. Patented June 1, 1915.

Application filed March 30, 1914. Serial No. 828,181.

To all whom it may concern:

Be it known that I, CHARLES WOKES, of the city of Toronto, in the county of York and Province of Ontario, Dominion of Canada, have invented certain new and useful Improvements in Chemical Fire-Extinguishing Apparatus; and I hereby declare that the following is a clear, full, and exact description of the same.

10 My invention relates to a fire extinguishing apparatus in which a chemical fire extinguisher is directly connected with the sprinkler system and the water supply, and the object of my invention is to so arrange 15 the apparatus that the withdrawal of part of the solution in the chemical tank through the opening of one or more of the sprinkler heads or the valve-controlled hose pipe will automatically cause the mixing of the chemical 20 solutions in the fire extinguisher for the generation of carbon dioxid which then escapes from said tank through the sprinkler system.

25 A further object of my invention is to utilize the gas pressure within the fire extinguisher to effect the opening of the valves controlling the passage of the water mains to the sprinkler system.

30 And a further object of my invention is to provide the fire extinguisher with means which will automatically operate a signal service when the mixing of the chemical solutions occurs.

35 For an understanding of my invention, reference is to be had to the following description and the accompanying drawings in which—

40 Figure 1, is a vertical section showing the fire extinguisher connected with the sprinkler system and with the water main, and also showing means whereby an electric signal is automatically operated; Fig. 2, is a vertical section through the valve mechanism controlling the flow of water from the 45 mains, taken on the line $a-a$, Fig. 1; Fig. 3, is a side elevation of the acid flask; and Fig. 4, is a detail of the means for locking the valve for the water main in an open position.

50 Like characters of reference refer to like parts throughout the specification and drawings.

55 The chemical tank a may be of any suitable shape and size, and within its upper end are two bearings b in which are journaled the trunnions c of the acid flask d , the trun-

nions being preferably located at one side of the vertical axial line of the flask so that it will be readily upset, as hereinafter described.

60 In the top of the chemical tank is an opening e closed by a removable cover f , the opening being of sufficient size to provide a means of access to the interior of the chemical tank for recharging purposes, and in the top of the tank at one side of the opening e is an orifice g leading to the safety valve h .

65 In the side of the tank is a valve-controlled pipe i , the entrance to which is slightly below the top of the acid flask d so that if there should be a leakage from the water main into the chemical tank the overflow will be taken care of before it can rise to the top of the acid tank and set up the generation of carbon dioxid.

70 At the bottom of the chemical tank is a draw-off cock j through which the chemical tank can be emptied whenever desired.

75 Fitted to the side of the chemical tank a is a pipe k forming part of the sprinkler system, and fitted to the pipe k are the sprinkler heads l . The pipe k is provided with a normally open valve m which can be closed to shut off the flow of chemical from said tank to the sprinkler system when so desired.

80 Fitted to the chemical tank is a valve mechanism controlling the flow of water from the water main to the fire extinguisher. This mechanism consists of a valve chamber o 90 fitted with an inlet pipe p provided with a check valve q .

85 The valve chamber o is provided with a valve seat r , between the inlet pipe p and its connection with the chemical tank a for the 95 sliding valve s .

90 The valve s is provided with a valve rod t mounted in suitable bearings $u u'$ and fixed on the valve rod t between the bearings is a diaphragm v having a small orifice w 100 through which a leakage of water may occur into the extension of the valve chamber o to balance the pressure on both sides of the diaphragm. The diaphragm v is located on the opposite side of the inlet pipe to the valve seat r and is of relatively greater area 105 than the valve s for the purpose hereinafter described.

110 The valve chamber o as shown in Fig. 1, extends beyond the diaphragm v and the extension is provided with a relief outlet x normally closed by a valve y opened by the

pressure of the diaphragm z . The diaphragm z is contained in a pressure chamber a' connected by a pipe b' with the chemical tank a .

5 Connected to the outlet pipe k is a valve-controlled hose pipe c' which can be manually opened at any desired time.

At the top of the tank is a pipe d' provided with a diaphragm e' having a contact point f' to engage with a contact g' and close the circuit from the battery h' through the conductors i' to the signal j' .

The acid flask d and the chemical tank a are filled with their respective chemical solutions, the level of the solution in the tank a being of a sufficient height to maintain the acid flask in a stable upright position. In the event of a fire occurring and either the sprinkler head l or the hose pipe c' being 10 opened, part of the solution in the chemical tank a will flow out through the pipe k and through either the sprinkler head or the hose pipe. When the solution in the tank a drops below the upsetting point of the acid flask d the latter rotates on its trunnions 15 head downward and empties its contents into the solution within the tank a ; carbon dioxid being then generated and the carbonated solution forced out through the sprinkler system or hose pipe, as the case may be.

The pressure of the carbon dioxid forces the liquid in the tank along the pipe i , thereby floating the valve i'' to its seat, and holding it there while any pressure remains in 20 the tank, as otherwise the gas would blow out past the valve; the same pressure being also exerted on the contact point f' to force it into engagement with the contact point g' to complete the circuit from the battery h' through the conductors i' to the signal j' . At the same time that this is taking place 25 the gas pressure in the tank a is exerted through the pipe b' on the diaphragm z and forces the diaphragm z against the valve stem z' of the valve y and moves the valve away from the valve seat to open the relief outlet x so that the contents in the extension of the valve chamber o will flow out 30 through the relief outlet x . Upon the relief of the water in the chamber o , the pressure in the tank will force the valve s open. While this is taking place, the contents of the chemical tank a are flowing out through the sprinkler heads l , the number of which 35 may be great or small, as the system may require, and the pressure in the chemical tank is, as a consequence, rapidly decreasing. When the pressure in the tank has fallen

below the pressure of the water in the inlet pipe p , the water pressure in that pipe forces 40 the check-valve q away from its seat, thus opening the communication from the inlet pipe p into the chemical tank a , the valve stem t being provided with a suitable locking device h' which holds the valve s in 45 an open position until it is manually closed again. When the valve s is open and while any chemical solution remains in the tank a the gas pressure therefrom on the check valve q will maintain that valve on its seat 50 and retard the flow of water from the inlet pipe p through the valve chamber o . When the solution in the chemical tank a is exhausted the water pressure in the inlet pipe p will lift the valve q from its seat and flow 55 freely through the tank to the pipe k of the sprinkler system and from the pipe k will flow out through the sprinkler heads.

By means of an apparatus of this kind I am able to discharge carbonic acid gas 60 through the sprinkler system into the burning premises and then automatically open the valve controlling the flow of water from the main, so that when the contents of the fire extinguisher have been discharged into 65 such premises the water will flow out through the sprinklers.

Having thus fully described the nature of my invention, what I claim as new and desire to secure by Letters Patent, is:

In a fire extinguishing apparatus, the combination of a chemical tank, a valve chamber connected therewith having an inlet and a waste outlet, a valve mechanism within the valve chamber comprising a valve 70 between the inlet and chemical tank, a rod for said valve, a diaphragm on the valve rod between the inlet and the waste outlet, said diaphragm having an orifice through which a leakage may occur into the valve chamber beyond the diaphragm, a valve controlling the waste outlet, a pressure chamber, a diaphragm therein for actuating the waste outlet valve, a connection between the pressure chamber and the chemical tank 75 whereby the generation of gas within the chemical tank will automatically actuate the diaphragm in the pressure chamber to open the waste outlet valve for the operation of the valve controlling the passage through 80 the inlet to the chemical tank.

Toronto, March 26th, 1914.

CHARLES WOKES.

Signed in the presence of—

CHAS. H. RICHES,
STANLEY RICHES.
